CLAIM

The ornamental design for an exterior surface configuration of a cabinet, as shown and described.

DESCRIPTION

FIG. 1 is a front view of an exterior surface configuration of a cabinet according to our novel design;

FIG. 2 is a left side view of an exterior surface configuration of a cabinet according to our novel design, the right side view being a mirror image thereof;

FIG. 3 is a top view of an exterior surface configuration of a cabinet according to our novel design;

FIG. 4 is a rear view of an exterior surface configuration of a cabinet according to our novel design; and,

FIG. 5 is a perspective view from the front right of an exterior surface configuration of a cabinet according to our novel design.

The broken lines depict environment and are not part of the claimed design. The bottom of the cabinet is flat and unornamented.
